L. BOMMER.
SPRING HINGE.

No. 40,879.

Patented Dec. 8, 1863.

Lorenz Bommer

UNITED STATES PATENT OFFICE.

LORENZ BOMMER, NEW YORK, N. Y., ASSIGNOR TO THE AMERICAN SPIRAL SPRING BUTT HINGE MANUFACTURING COMPANY.

IMPROVEMENT IN SPRING-HINGES.

Specification forming part of Letters Patent No. 40,879, dated December 8, 1863.

To all whom it may concern:

Be it known that I, LORENZ BOMMER, of the city of New York, in the county of New York and State of New York, have invented certain new and useful Improvements in Spring Butt-Hinges; and I do hereby declare that the following is a full and exact description thereof, reference being had to the accompanying drawings, and to the letters of reference marked thereon, in which—

Figure 1 is a vertical diametrical section through the common eye of the hinge, showing the manner of holding the ends of the spiral spring, and also showing the inside cylinder or hollow pintle. Fig. 2 is a horizontal section through Fig. 1 taken in the plane indicated by the dotted line *xx*, marked thereon. Figs. 3 and 4 are perspective views of the top and bottom caps of the eye of the hinge.

Similar letters of reference indicate corresponding parts in the several figures.

This invention relates to certain improvements in that class of butt-hinges wherein a spring is introduced within the eye of the hinge for the purpose of either opening or closing a door, gate, &c., to which the hinges may be affixed.

It consists, first, in the introduction within the hollow eye of the hinge of a hollow stem or cylinder, which is intended to receive within it a spiral spring, and which is also intended as an axis or bearing for the eyes of a sectional-eyed hinge, as will be hereinafter fully described and represented.

To enable those skilled in the art to make and use my invention, I will proceed to describe its construction and operation.

A is the leaf or wing of one half of the hinge, and *a a'* are the eyes which are cast with and belong to this wing. *B* is the leaf of the other half of the hinge, and *b b'* are its eyes. The eyes *a a' b b'* of this hinge are of an equal diameter, and of such a diameter as to admit of the introduction within them of a very strong spiral spring, *C*, and a cylinder, *D*, which latter contains the spring. The cylinder *D* is made of very stout sheet-iron and fits loosely within the common eye of the hinge, as shown in Figs. 1 and 2 of the drawings. This cylinder *C* is not quite as long as

the common eye of the hinge, and therefore it does not extend out to the ends of the eye. A space is thus left at each end of the eye of the hinge for the reception of the necks of the two caps *E F*. The use of the cylinder *D* dispenses with a central solid stem, which has been hitherto used in the sectional-eyed hinges, and admits of the employment of a spiral spring, *C*, for without such a cylinder, *D*, it will be readily seen that a hollow sectional-eyed hinge would not have any axial bearing. This hollow sectional-eyed hinge is much stronger than that class of hinges which have only two eyes, or one eye on each leaf, as instanced in Patent No. 36,976, and for all large doors, gates, &c., the sectional eye-hinge is more desirable. I have therefore introduced within the hollow eye of the hinge the hollow cylinder, which covers the joints and serves the purpose of an axis or bearing for the eyes of the two leaves *A B* and keeps the two parts of the hinge together, allowing them at the same time to have the usual free swinging motion. I thus dispense with a central axis or solid pintle common in sectional eye-hinges, and introduce within the cylinder *D* a strong spiral spring, *C*, which is nearly if not quite as long as the cylinder *D*. The ends of the wire of this spring *C* are bent diametrically across the ends of this spring, so as to pass between the prongs of the bifurcated lugs *G G'* on caps *E F*, as shown in Figs. 1 and 2 of the annexed drawings, for the purpose of being held rigidly in their places by said lugs.

The method hitherto adopted of passing the ends of the spring wire into perforations which were made in the ends of the caps *E F*, as described in Patent No. 36,976, has been found objectionable, as the ends of the wire were liable to slip out of their places, the wire to bend, &c.; but where the ends of the spring-wire are bent, as hereinabove described and represented, and passed between the forks of the bifurcated lugs *G G'* the ends of the spring will be substantially held in their places.

The two caps *E F* differ somewhat one with the other in their construction. The lower cap, *F*, has an annular depression or neck which fits into the end of eye *a'* of leaf *A*. The flange *e* abuts against the end of eye *a'*, and pin *i*,

which passes diametrically through eye a' and cap F, keeps this cap rigidly fixed to the eye a' of leaf A.

G' is the bifurcated lug of cap F, which holds the lower end of the spring C.

Cap E, or the upper cap, which is to be rotated in the operation of increasing or diminishing the action of spring C upon the leaves of the hinge, consists of an enlarged perforated portion, k , a reduced perforated portion, n , an annular groove, p , flange p' , and the bifurcated lug G, which latter corresponds with the lug or cap F. The portions $n p p'$ and lug G pass into the eye b' of leaf B, and the portions n and p fit snugly but not very tightly within this eye b' .

The perforations $s s$ in portion k are used merely for the purpose of receiving the end of a lever for turning the cap E to the right or to the left; but the perforations $v v$ in the neck n are intended to receive the end of the setting-pin w , which passes through a perforation near the upper end of the eye b' of leaf B and locks or affixes the leaf B to the cap E. The annular groove p receives a number of screw-pins $f f$, which are tapped through eye b' of leaf B. The ends of these pins $f f$ project into the groove p and allow the cap E to rotate freely, but keep this cap from being forced or drawn out of its place. It will now be seen

that cap F is rigidly fixed to the eye a' of leaf A by means of pin i , and that cap E can be rotated so as to wind up or unwind spring C, and also that this cap E can be fixed to the eye b' of leaf B by introducing pin w through eye b' into any one of the radial perforations $v v$ in neck n . When pin w is not in its place, the hinge will work like any ordinary hinge without a spring, and by rotating the cap E so as to coil up spring C the action or force of this spring can be increased to any desired degree.

Having thus described my invention, what I claim as new, and desire to secure by Letters Patent, is—

1. The hollow cylinder D, or its equivalent, when applied to the sectional spring-hinge essentially as and for the purposes herein set forth.
2. The annular groove p in cap E, or its equivalent, in conjunction with pins $f f$, as and for the purposes herein set forth.
3. The combination of cylinder D, caps E F, and spring C, or their equivalents, substantially as and for the purposes herein set forth.

LORENZ BOMMER.
